J. R. STIEGELMEYER

LOAD EQUALIZING CAR BRAKE

Filed June 4, 1923

INVENTOR
John R. Stiegelmeyer,
BY
Arthur M. Hood.
ATTORNEY

UNITED STATES PATENT OFFICE.

JOHN R. STIEGELMEYER, OF INDIANAPOLIS, INDIANA.

LOAD-EQUALIZING CAR BRAKE.

Application filed June 4, 1923. Serial No. 643,203.

To all whom it may concern:

Be it known that I, JOHN R. STIEGELMEYER, a citizen of the United States, residing at Indianapolis, in the county of Marion and State of Indiana, have invented a new and useful Load-Equalizing Car Brake, of which the following is a specification.

The object of my invention is to provide a mechanism, by means of which the brakes of vehicles, such for instance as freight and passenger cars, may be applied to the supporting wheels of the vehicle proportionally to the load carried by the vehicle at the time of the application of the brakes.

By means of this mechanism, a series of cars coupled into the same train, will have their brakes applied to their wheels by forces proportional to the weights carried by the bodies of the cars although the forces used in the application of the brakes will be the same in all cars.

The accompanying drawings illustrate my invention: Fig. 1 is a side elevation of a truck, of common form, of a freight car, equipped with my improved brake applying mechanism; Fig. 2, a transverse vertical section on line 2—2 of Fig. 1; Fig. 3, a section on line 3—3 of Fig. 1 and Fig. 4, a fragmentary sectional detail.

In the drawings, 10, 10 indicate aligned wheels of a body-supporting truck connected, in the usual manner, by frame 11. A complete truck comprises two pairs of wheels 10, 10 and two frames 11, 11 and the two frames 11, 11 are connected by a transverse spring-plank 12 which extends from one frame to the other in the usual manner.

Also, extending between the two plates 11 is the bolster 13 upon which the car body 14 is supported, springs 15 being interposed between the spring-plank 12 and the bolster 13.

Thus far the construction is common and standard.

In my present construction, however, I interpose between the spring-plank 12 and the springs 15 of each side, a spring-cup 16 provided with vertical sides 17, 17, the outer faces of which are provided with pockets 18, 18, the upper wall of each of said pockets forming a cam-engaged surface.

Arranged alongside of each pocket wall 17 is a plate 20 the inner face (i. e., the face immediately adjacent the adjacent wall 17)

of which is provided with a pocket 21, the lower wall 22 of which forms a cam-engaged face.

In each pocket formed by the two facing pockets 18 and 21 I mount a cam 23 which is provided with flanking trunnion portions 24, 24, and an operating lever 25. Wall 17 is vertically slotted, in the bottom of pocket 18, by a slot 26 having a horizontal dimension equal to the diameter of a trunnion 24 and a vertical dimension in excess thereof. Similarly, plate 20 is vertically slotted, in the bottom of pocket 21 by a slot 27 having a horizontal dimension equal to the diameter of the adjacent trunnion 24 and a vertical dimension in excess thereof. A headed bolt 28 is passed through the trunnioned cam structure 23, 24, the head thereof engaging the inner face of wall 17 and the outer end passing through a bearing bracket 29, vertically slotted at 29', carried by the spring pocket 16, the bolt being held in place by suitable retaining means 30.

Bolted to the spring-plank 12 are two pairs of bearing brackets 31, 32, each of said bearing brackets being provided at its upper end with a bearing for the reception of the fulcrum 35 of a brake-shoe lever 36, to which a brake-shoe 37 is pivoted. Each fulcrum 35 is provided with a pair of arms 38, 38, which extend toward cams 23 and the outer ends of each pair of said arms 38 are connected by pin 39 passed through horizontal slots 40 in plates 20.

Brackets 31 are similarly provided at their upper ends with bearings for the reception of the fulcrum 35' of a brake lever 36' to which a brake-shoe 37' is pivoted, and said fulcrum 35' is provided with inwardly extending arms 38', like arms 38, connected by pin 39' which also extends through slots 40.

Brackets 31 are also provided with bearing brackets 42 in which is journaled the main operating shaft 43 which extends across beneath the car from one bracket 31 to the other. Secured to shaft 43 near each end are arms 44, one for each cam 23, and each of these arms is connected by a link 45 with a cam arm 25.

It will be noted that by this construction there are two cams 23 arranged to float between each spring pocket 16, and the adjacent pair of brake levers 36 and 36', and that all of the cams are capable of simultaneous

actuation by a rocking of the main shaft 43.

Secured to shaft 43 is a main operating lever 46 which is to be connected in any suitable manner to the usual brake operating piston of an ordinary air brake system (not shown).

In operation, and in normal running condition, the load in car body 14 is supported by the truck through the medium of springs

10 15 in the usual manner, the cams 23 floating in non-active position. Whenever braking force is applied to the lever 46, the cams 23 will be swung so as to simultaneously engage the surfaces 19 and 22 so that said 15 cams will be interposed between the spring pockets and the springs 15 so that the load in the car body will be thus utilized as an abutment against which the cams of the braking mechanism act upon the brake shoes.

20 It will be apparent, from what has been said above, that in the case of two cars of the same train, one of which is loaded and the other of which is empty, a train line reduction which will be sufficient to cause the 25 operating lever 46 of the empty car to move through its complete possible movement, thereby swinging cams 23 of that car as far as they will swing (limited by the possible movement of the piston or by any 30 other suitable means), so that the cams of this car will be fully interposed between the brakes and the car body, will be sufficient to produce, in the loaded car, a very much less movement of the cams 23.

35 It will also be apparent that, under such conditions, the resistance offered by the loaded car body, as an abutment for the cams of that car will permit the transference, to the brake shoes, of the entire braking force 40 applied to lever 46 whereas, in the unloaded car, some of that braking force will be resisted by the stop which limits the movement of the cams of that car and that consequently the amount of braking force which is

45 effective upon the wheels of the loaded car will be greater than the amount of braking force which is effective upon the wheels of the unloaded car. In other words, the applied forces to the braking mechanism of 50 the several cars of the train being, of necessity, equal to each other, yet nevertheless, through the medium of my mechanism, the effective braking forces applied through the shoes to the wheels of the several cars, will 55 be proportional to the loads carried by the bodies of those cars. Consequently, a heavily loaded car, having a greater momentum, will be more heavily braked, proportionally to its load, than an unloaded or a lighter 60 loaded car, and therefore the effective braking forces acting upon the several cars of the train will be proportional to the forces to

be braked and substantially uniform in effect throughout the train.

As a consequence of this construction, the 65 several cars of a train, irrespective of the loads carried, will be braked at substantially uniform rates so that the danger of breaking a train in two or the danger of the crushing of an empty in front of a loaded car, which 70 now exists, is avoided.

I claim as my invention:

1. The combination, in a vehicle comprising supporting wheels and a supported load-carrying body, of brake-shoes arranged to 75 act to brake said wheels, and means for actuating said brake-shoes, said means comprising elements between the brake-shoes and load-carrying body whereby the weight 80 of the load-carrying body becomes the abutment for said brake-actuating means.

2. The combination, in a vehicle comprising supporting wheels, a supported load-carrying body, and a load-carrying spring 85 interposed between the load-carrying body and the wheels, of brake-shoes arranged to act to brake said wheels, and means for actuating said brake-shoes, said means comprising elements between the brake-shoes and weight of the load-carrying spring 90 whereby the load-carrying body becomes the abutment for said brake-actuating means through said spring.

3. The combination, in a vehicle comprising supporting wheels and a supported load-carrying body, of brake-shoes arranged to 95 act to brake said wheels, levers carrying said shoes, a cam-engaged member associated with the load-carrying member, a second cam-engaged member connected to said 100 levers, a cam interposed between said two cam-engaged members whereby the load-carrying body forms an abutment for said cam, and means by which the cam may be actuated.

4. The combination, in a vehicle comprising supporting wheels, a supported load-carrying body, and a load-carrying spring 110 interposed between said wheels and body, of brake-shoes arranged to act to brake said wheels, levers carrying said shoes, a supporting cup for said spring, a cam-engaged member associated with said cup, a second cam-engaged member connected to said levers, a cam interposed between said two cam-engaged members whereby the load-carrying body forms an abutment for said cam through 115 the spring, and means by which the cam may be actuated.

In witness whereof, I have hereunto set 120 my hand at Indianapolis, Indiana, this 2nd day of June, A. D. one thousand nine hundred and twenty-three.

JOHN R. STIEGELMEYER.

Certificate of Correction.

I hereby certify that in Letters Patent No. 1,526,442, granted February 17, 1920, upon the application of John R. Stiegelmeyer, of Indianapolis, Indiana, for an improvement in "Load-Equalizing Car Brakes," an error appears in the printed specification requiring correction as follows: Page 2, line 90, claim 2, strike out the words "weight of the" and insert the same before the compound word "load-carrying" in line 91 of the same claim; and that the said Letters Patent should be read with this correction therein that the same may conform to the record of the case in the Patent Office.

Signed and sealed this 24th day of March, A. D. 1925.

[SEAL.]

KARL FENNING,
Acting Commissioner of Patents.
